CLAIM

The ornamental design for a smoke generator, as shown and described.

DESCRIPTION

FIG. 1 is a top perspective view of a smoke generator in accordance with the present invention.

FIG. 2 is a bottom perspective view showing the smoke generator of FIG. 1.

FIG. 3 is a front elevation view showing the smoke generator of FIG. 1.

FIG. 4 is a rear elevation view showing the smoke generator of FIG. 1.

FIG. 5 is a left elevation view showing the smoke generator of FIG. 1.

FIG. 6 is a right elevation view showing the smoke generator of FIG. 1.

FIG. 7 is a top plan view showing the smoke generator of FIG. 1.

FIG. 8 is a bottom plan view showing the smoke generator of FIG. 1; and,

FIG. 9 is a top perspective view with the lid separated showing the smoke generator of FIG. 1.

The broken lines shown in the Figures depict portions of the smoke generator and form no part of the claimed design.

1 Claim, 8 Drawing Sheets
